UNITED STATES PATENT OFFICE.

JAMES L. KEITH, OF ST. LOUIS, MISSOURI.

RAILROAD-TRAIN STOP.

1,312,077.

Specification of Letters Patent.

Patented Aug. 5, 1919.

Application filed July 6, 1917. Serial No. 178,981.

To all whom it may concern:

Be it known that I, JAMES L. KEITH, a citizen of the United States, residing at St. Louis, State of Missouri, have invented certain new and useful Improvements in Railroad-Train Stops; and I do hereby declare the following to be a full, clear, and exact description of the invention, such as will enable others skilled in the art to which it appertains to make and use the same.

This invention relates to improvements in a railroad train stop and has for one of its objects the provision of a device of this character whereby trains entering upon the same block will be automatically stopped.

Another object of this invention is the provision of means whereby the train crew of one train can communicate with the other train crew on the other train when in the same block.

A further object of this invention is the provision of an electric motor for automatically applying the air brakes of the train when entering the block with another train.

A further object of this invention is the provision of means for automatically stopping the motor after applying the air brakes.

A still further object of this invention is the provision of a railroad train stop of the above stated character, which shall be simple, durable and efficient, and which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which:—

Figure 1 is a transverse sectional view of a locomotive illustrating my invention applied thereto,

Fig. 2 is a diagrammatical view of the wiring diagram of my invention,

Fig. 3 is a vertical sectional view of one of the contact arms carried by the locomotive.

Fig. 4 is a fragmentary perspective view of the communicating ends of two blocks,

Fig. 5 is an end elevation of the hanger, and

Fig. 6 is a plan view of a railroad track having a switch.

Fig. 7 is a fragmentary plan view drawn on an enlarged scale of the switch.

Fig. 8 is a fragmentary side elevation illustrating the ends of the blocks.

Referring in detail to the drawings, the numeral 1 indicates as an entirety a locomotive which is provided with the usual air brake system 2 controlled by a valve 3. 65 Branch pipes 4 are connected with the brake system 2 which has a controlling valve 6 that is provided with a handle 7. The handle 7 has pivotally connected thereto a bar 8 which meshes with a pinion 9. The pinion 70 9 is formed upon an enlarged gear 10. The enlarged gear 10 is journaled within the locomotive 1 in any desired manner and meshes with a pinion 11 formed upon a gear 12. The gear 12 is journaled in the locomotive in 75 any well known manner and meshes with a pinion 13 of an electric motor 14 located within the cab of the locomotive.

Hangers 15 are secured upon each side of the locomotive as clearly illustrated in Fig. 1 80 and have slidably mounted therein rods 16 which rods are normally urged downwardly by springs 17 that have one of their ends disposed against lugs 18 carried by the rods 16 and against supporting brackets 19 in 85 the hangers 15. The lower ends of the rods 16 are bifurcated to form a pair of relatively spaced arms to which are journaled contact wheels 20. The rods 16 have connected thereto conductors 21 and 22. The conductor 90 21 is connected to a battery 23 carried by the locomotive 1 and which has connected thereto a conductor 24 that connects with a telephone 25. A conductor 26 is connected to the conductor 24 and to the motor 14. A conductor 27 is connected to the motor and to a movable switch arm 28 which is carried by the locomotive. A contact arm 29 is located adjacent the switch arm 28 and is normally engaged by the same under the influence of 100 a spring 30 engaging the switch arm 28. A conductor 31 is connected to the contact arm 29 and to a pole 32 which has the conductor 22 connected thereto. A conductor 33 is connected to the pole 32 and to the telephone and placing the telephone in circuit with the remaining portions of applicant's 105 invention.

Wires or rods 34 are located along each side of the rails of a track as illustrated in 110

Fig. 4. Supports 35 are secured to the ties of the track and support one of the ends of the wires or rods 34 of one block, while the supports 36 support the ends of the rods or wires 37 of another block. Auxiliary supports 35' support the rods between the supports 35 and 36.

When a block is occupied by a train, upon a second train entering the same block 10 traveling in the same direction, an electric circuit will be completed to the motors 14 upon each of the trains owing to the contact wheels 20 traveling upon the wires or rods 34. The motors are then started in motion 15 which causes the rack bars 8 of both trains to move in the direction of the motors operating the valves 6 to apply the air brakes thus stopping both of the trains. An arm 38 is carried by the rack bar 8 and as 20 the same moves rearwardly during the operation of the motor, it engages the contact arm 28, disengaging the same from the contact 31, thus breaking the electric circuit to the motor.

25 My invention is adapted for use on double track systems or where the trains travel over the tracks in the same direction. To prevent the battery of one train from working in opposition to the battery of another train 30 when said trains are in the same block, the train despatcher when sending the various trains out on their runs gives orders to have the positive and negative poles of the batteries so connected to their circuits of the 35 various trains that the battery of a following train will not work in opposition to the battery in the train in ahead or the first train.

When the trains have entered upon the 40 same block the crews of the trains may communicate with each other by way of the telephone 25 and after the electric current has been broken to the motors, the telephone 45 25 of each train will still remain in operation thus permitting the crews to decide upon their further procedure.

When a switch 39 is located upon the main track of a railroad as illustrated in Fig. 6, wires or rods 40 and 41 are located along- 50 side of each rail thereof and the wire or rod 40 is connected with the wire or rod 34 upon the main track while the rod 41 is normally disconnected from the other wire or rod 34 of the main track and has a contact 42 there- 55 on adapted to move into engagement with the other wire or rod 34 of the main track when the switch is open or in a position to permit a train to pass from the main track on to the switch. A conductor 44 is con- 60 nected to the rods 40 and 41 whereby upon a train entering the block having the switch 39 in an open position, an electric circuit

will be completed to the motor 14 of the train entering the block so as to apply the brakes which prevents the train from running on 65 the open switch.

Ratchet wheels 45 are journaled in the hangers 15 and have formed thereon a plurality of projecting arms 46. Spring actuated dogs 47 are carried by the hangers and normally engage the ratchet wheels 45. Resilient arms 48 are secured to the arms 16 and are adapted to move into engagement with the ratchet wheels when said arms are moved upwardly against the tension of the 75 springs 17, as for instance, when the train is leaving one block as illustrated at A, the rods 16 are moved upwardly by the supports 35 and by so doing rotates the ratchet wheels to position one of the arms thereon to support the rods 16 in an elevated position by engaging the lugs 50 upon the rods 16. The rods 16 are supported in this position until the contact wheels 20 engage the supports 36 which causes the ratchet wheels 45 to be 85 again moved upwardly owing to the supports 36 being higher than the supports 35 which disengaging the arms 46 from engagement with the lugs 50 which permit the arms 16 to move downwardly under the influence 90 of the springs 17 permitting the contact wheels 20 to follow the rods or wires 37.

The heretofore described construction is employed for preventing the wheels 20 of the spring pressed rods 16 from being forced 95 to a plane below the rods or wires of said blocks at their ends when the train is passing from one block to another.

While I have shown and described the preferred embodiment of my invention, it 100 will be understood that minor changes in construction, combination and arrangement of parts may be made without departing from the spirit and scope of the invention, as claimed.

105 What I claim is:

A railroad train stop including an engine having an electrical brake operating means and an open electric circuit associated therewith, spring pressed members connected to the engine and to the circuit, block forming members engaged by said spring pressed members and having their ends elevated, and ratchet means affected by the elevated ends for holding the spring pressed members elevated when the engine passes from one block to another.

110 In testimony whereof I affix my signature in presence of two witnesses.

115 JAMES L. KEITH.
